UNITED STATES PATENT OFFICE.

FREDRICK J. HEIDEMAN, OF DETROIT, MICHIGAN, ASSIGNOR, BY MESNE ASSIGNMENTS, TO THE ISKO COMPANY, OF CHICAGO, ILLINOIS, A CORPORATION OF DELAWARE.

COMPRESSOR.

1,401,102

Specification of Letters Patent. Patented Dec. 20, 1921.

Application filed January 19, 1917. Serial No. 143,311.

To all whom it may concern:

Be it known that I, FREDRICK J. HEIDEMAN, a citizen of the United States, and resident of Detroit, Wayne county, State of Michigan, have invented certain new and useful Improvements in Compressors, of which the following is a specification.

This invention relates to compressors or like mechanism, and particularly to two cylinder compressors in which the pistons are operated by eccentric and strap connections.

One of the objects of the invention is to provide a compressor of compact form and efficient operation.

15 Another object of the invention is to provide a novel and simple construction of connecting rod and eccentric mechanism for operating the piston of a compressor or like machine.

20 Another object of the invention is to provide a novel and simple cylinder head and valve construction for compressors.

Other objects of the invention will appear from the following description taken

25 in connection with the drawings, which form a part of this specification, and in which:

Figure 1 illustrates a compressor built in accordance with this invention, the left half of the view being in elevation except for a 30 cut away portion of the cylinder and the right half being in vertical section;

Fig. 2 is a vertical section through one of the cylinders taken at right angles to the section of Fig. 1;

35 Fig. 3 is a horizontal section on the line 3-3 of Fig. 2; and

Fig. 4 is a section through the detachable cylinder head.

The invention is shown in the drawings 40 in the form of a two cylinder compressor such as may be used in connection with a refrigerating apparatus of the compression type. Changes and modifications may be made in this form without departing from 45 the spirit of the invention.

Referring to the drawings, 10 represents a casting which as shown may constitute the crank case 11 and the two cylinders 12 arranged with their axes in parallel but offset 50 on opposite sides of the crank shaft 13. This crank shaft is mounted in suitable bearings 14 in the crank case and is provided with packing 15 to prevent leakage. One side of the crank case may be formed with an opening 11' closed by a removable cover 10' in

which one of the bearings 14 is arranged. Two eccentrics 16 are keyed on the shaft 13 side by side and preferably about 180 degrees apart. Also preferably the relative arrangement of the cylinders and eccentrics 60 is such that each eccentric is lined up with its respective cylinder as shown for instance in Fig. 2.

By this offset arrangement of the cylinders the eccentrics may be brought close together 65 and a very compact cylinder and crank case casting becomes possible.

The connecting rod construction for each cylinder comprises a rod 17 threaded into a one piece strap 18 which surrounds the eccentric, and a ball and socket connection to a piston 17'. Thus the piston has a socket 19 in which a ball member 20 fits being held therein by a ring 21 threaded into the piston. The upper end of the rod 17 is rigidly 70 connected to the ball 20 as by a pin or rivet 22. This piston connection of the connecting rod serves to position the eccentric strap axially on the eccentric.

The cylinder heads are formed by a head 80 plate 23 which covers the tops of both of the cylinders and a cover 24 arranged over the head plate. In the head plate are openings 25 over each cylinder and in each such opening is an outlet valve 26, shown as of 85 the poppet type. The valve is pressed against its seat 27 by a pair of springs 28 retained by a guide ring 29, which ring forms a guide for the valve stem 30 and is itself retained over the opening 25 by the 90 cover 24. The cover and head plate are detachably secured to the cylinders by bolts 31 as shown. The ring 29 has openings 32 which communicate with the opening 25 on one side and with a passage 33 in the cover, 95 on the other side. This passage 33 forms the outlet conduit from the cylinders.

The inlet for gas or other substance is provided in the form of a pipe 34 communicating with the crank case, and a conduit or 100 passage 35 formed in the casting 10 between the cylinders and opening into the cylinders as at 36 at a point to be uncovered by the piston at the lower or inner end of its stroke.

105 When the compressor is used as part of a refrigerating unit, the crank case may be provided with a charging opening 37 in which is a plug 38 and a cap 39, whereby the refrigerant may be received into the system. 110

Having thus described my invention, what I claim and desire to secure by Letters Patent is:—

1. In a compressor, the combination of a crank case and cylinders, a crank shaft in the crank case, pistons and connecting rods, a conduit leading to the crank case, a conduit between the cylinders leading from the crank case to a port in each of the cylinders, and an outlet conduit.
2. In a compressor the combination of a crank case and cylinders formed in a single casting and having a by-pass conduit leading from the crank case to ports in the cylinders to be uncovered by the pistons at the inner end of their stroke, an inlet conduit for the crank case, and a head for the cylinders comprising outlet conduits therefrom and housing the outlet valves.
3. In a compressor, the combination of a crank case and a cylinder, a crank shaft in the crank case, a piston and a connecting rod, a conduit leading to the crank case, an uninterrupted conduit leading from the crank case to a port in the cylinder wall, and an outlet conduit from the cylinder.
4. In a compressor for compressing a refrigerant, in combination, a crank case, a cylinder secured thereto, a shaft in the crank case, a piston in the cylinder, mechanism connecting the shaft and piston to reciprocate the latter, a conduit supplying refrigerant to the crank case, an uninterrupted conduit connecting the crank case and an inlet port in the cylinder adjacent the suction end of the piston stroke and an outlet for the cylinder.
5. In a compressor for compressing a refrigerant, in combination, a crank case, a cylinder secured thereto, a shaft in the crank case, a piston in the cylinder, mechanism connecting the shaft and piston to reciprocate the latter, and a conduit supplying refrigerant to the crank case, said cylinder having an enclosed passage in the wall communicating at one end with the crank case and at its other end in communication with the cylinder at a point adjacent the suction end of the piston stroke, said cylinder also having an outlet.

In testimony whereof I affix my signature.
FREDRICK J. HEIDEMAN.
